UNITED STATES PATENT OFFICE.

WILLIAM T. DUNFORD, OF NEW YORK, N. Y., ASSIGNOR TO SHURLOC ELEVATOR SAFETY CO., INC., A CORPORATION OF NEW YORK.

ELEVATOR SAFETY SYSTEM.

1,344,266.

Specification of Letters Patent. Patented June 22, 1920.

Application filed August 10, 1914. Serial No. 856,123.

To all whom it may concern:

Be it known that I, WILLIAM T. DUNFORD, residing at 364 West 117th street, city, county, and State of New York, have invented certain new and useful Improvements in Elevator Safety Systems, of which the following is a specification.

The invention is an improved safety system for elevators, the general object being to provide a simple, compact and reliable construction and arrangement of parts on the car and at the several landings, whereby the car can be moved from a landing only in event of the door being locked. The invention more particularly comprises a construction and combination of parts enabling the door to be unlocked and the controller simultaneously rendered inoperative by a pedal on the car, and wherein the train of mechanism for locking the controller is mounted wholly on the car, thus permitting the controller to be located in the most advantageous position, preferably at the side of the car, while another train or branch transmits motion to a car contact by which the mechanism at each landing is operated to unlock the landing doors. The invention also comprises in such a construction means for engaging and holding the car contact in its shifted position, thus holding the connected controller-locking mechanism against release, until the door in its closing movement disengages such means from the car contact, whereupon the car contact automatically returns to its original position. A further feature of the invention resides in the construction of the door-locking mechanism, whereby opening movement of the doors is barred at two positions thereof, namely closed position and a position a predetermined distance therefrom, in conjunction with which provision means are provided whereby the detent for holding the car mechanism is released by the door as each locking position is reached, so that a quick start from the landing can be effected, before the door has fully closed, without leaving the same in a condition permitting it to be pushed open from the outside. The system is applicable to existing cars and controllers of different types, and other objects and features of the invention will become apparent as the specification proceeds.

In the accompanying drawings illustrating the invention:

Figure 1 is a fragmentary perspective

view of an elevator car, showing the car parts of the invention;

Fig. 2 is a fragmentary perspective view of a landing and a landing door, showing the landing mechanism in normal condition, that is to say, with the door closed and locked, the car contact being represented in dotted lines; Fig. 3 is a front elevation of the parts shown in Fig. 2;

Fig. 4 is a view similar to Fig. 3, showing the door partially open;

Fig. 5 is a vertical cross-section through Fig. 4;

Fig. 6 is a detail elevation of the latch;

Fig. 7 is a side view of the lower part of Fig. 6;

Fig. 8 is a side view of the detent;

Fig. 9 is a plan view of the controller;

Fig. 10 is a detail view in vertical section taken at the pedal;

Fig. 11 is a detail plan view of the switch;

Fig. 12 is a sectional detail view illustrating the locking devices at the controller; and

Figs. 13 and 14 are detail perspective views of parts shown in Figs. 9 and 12.

Each landing door, of which one is shown and designated 2, is provided with a lock or catch, by which the door is automatically engaged at or before the conclusion of its closing movement, so that it cannot be opened from the outside. By locking is not meant necessarily that the door is held immovable, but that it is held against opening movement. Thus, as will presently be described, the door at the first of its locking positions can be moved farther in the closing direction but not beyond this position in the opening direction.

The locking mechanism preferably comprises a horizontally extending bar or latch 3 pivoted at 4 on a vertical axis in a casting or recess 5 in the face of the shaft below the landing floor. A suitable outwardly projecting contact member 6 is connected to the latch 3 in an appropriate manner, being preferably mounted on a short arm 7 rigidly united with the latch and extending in the same direction from the pivot. The latch is urged outward by a spring 42 and is provided with two locking lugs 8 and 9 spaced lengthwise thereon for engagement with a suitable part on the door, such as an arm 10 projecting downward from the forward portion of the door and suitably formed to clear the edge of the landing and

to operate in the gap between the same and the car. In the particular construction shown the intermediate portion of the arm is extended sidewise because of the position 5 of the locking mechanism somewhat to one side of the door opening. The relation of the lower extremity of the door projection 10 and the two locking lugs 8 and 9 is such that the door may be locked against opening 10 movement when closed and also at a predetermined distance in advance of closing. It will be understood that when the first locking lug 8 is reached in the closing movement the distance remaining between 15 the forward edge of the door and the side of the door opening should be insufficient to permit a person to squeeze through.

The car 11 is provided with a controller 12 having a hand lever 13, which swings 20 about a horizontal axis 14. The controller is located at the side of the car toward which the landing door slides in opening. A car contact in the form of a vertically elongated shoe 15 is located toward the side 25 of the car remote from the controller, in position to be brought opposite the landing contact 6, with which it cooperates. In the particular construction shown the car contact is fixed to the forward end of a slide bar 16 30 mounted in suitable bearings 17 beneath the car, at right angles to the landing. A pedal 18 located in the floor of the car at a point conveniently adjacent the controller enables the operator to project the car contact 15 in 35 order to unlock the door, and at the same time actuates a train of parts wholly on the car to lock the controller lever 13 in mid-position; this being the position which it occupies when the car is at rest. The specific arrangement of parts may naturally be 40 varied; but in the preferred construction a rock shaft 19 journaled in bearings 20 transversely beneath the floor of the car and operated by the pedal is connected adjacent 45 one end by an arm 21 with the slide bar 16 of the car contact 15, and at the other end is provided with a substantially horizontal arm 22 which connects with the lower end of a vertical locking rod 23 extending upward 50 within the car behind the controller. It will thus be perceived that a branched or double train of connections wholly on the car extends from the pedal, on the one hand to the car contact, and on the other hand to 55 the controller-locking device. Preferably, as shown, the transverse rock-shaft member 19 is common to both trains.

The rod 23 slides in suitable guides and at its upper end cooperates with a member 60 24, which is pivoted at 25 on a vertical axis to the top of the controller casing and has a tail-piece 26 provided with an opening 27. The forward part of this member is forked as shown at 28 so as to be engaged and 65 rocked by the controller lever 13 in order

that the opening 27 may register with the upper end of the locking rod 23 when the controller is central, while at other times the solid portions of the tail-piece obstruct the upward movement of the said rod and 70 consequently prevent the operation of the pedal 18 and the car contact 15. In view of the fact that the controller lever 13 has a considerable range of movement, it is desirable to form the engaging portion of the 75 member 24 in the manner shown, so that the member is connected with the lever only during a limited extent of its movement at each side of center; when the controller lever is moved beyond such point, it leaves 80 the member 24 in diagonal position in readiness to be engaged on the reverse movement of the lever.

The controller may not only be rendered 85 inoperative by locking the lever in mid-position but also by the operation of a switch controlling a circuit at a point outside of the controller. This circuit is preferably the main car circuit, and is broken by a part 90 of the mechanism set in motion by the depression of the pedal 18. In the particular construction shown, circuit controlling means are provided at 78 in connection with the slide bar 16, the construction being such that when this bar is in its rearward or normal position, the car circuit indicated by the conductors 29 is closed at this point, while when the bar is moved forward the circuit is broken. The circuit controlling provisions may also be arranged to close the 95 circuit 30 of the floor light 31 simultaneously with the locking of the controller lever and the breaking of the car circuit.

In accordance with the invention means are provided for holding the car contact 105 15 and consequently the controller-locking mechanism in their shifted or abnormal positions. Such means may be widely varied, but in the preferred construction comprise a spring-urged detent 32 mounted at the 110 binding within the casing 5. In the particular embodiment of the invention illustrated said detent is a bell-crank member pivoted at 33 with its upper arm 34 adapted to project into the path of the door part 10 and 115 provided on its lower arm with a conical roller 35 held in place by a screw 50 and adapted to engage behind, that is at the car side of the car contact 15. A second bell-crank element 37 pivoted at 38 at a 120 distance from the element 32 corresponding approximately to the distance between the locking lugs is provided for the purpose of enabling the door to disengage the detent from the car contact when the door in its closing movement has reached or approximately reached the first locking position. To this end the upper arm 39 of this bell-crank is disposed in the path of the part 10 and its lower arm is connected with the 130

lower arm of the detent element by a pivotal link 40. The spring 41 which urges the detent to the left is shown connected at one end with this link and at the other end with a stationary abutment, serving it will be understood to give both the arms 34 and 39 a bias into the path of the part 10.

In operation, the operator stops the car opposite the landing by moving the controller lever to mid-position. He then depresses the pedal 18, thereby projecting the car contact 15 so as to press the landing contact 6 and latch 3 back toward the wall of the shaft. This removes the locking lug 9 from in front of the door part 10, so that the door may be opened by sliding it to the right. Simultaneously with the unlocking of the door, the controller lever is locked in its inoperative position by the raising of the rod 23 into engagement with the hole 27 in the member 24. At the outset of the opening movement of the door the part 10, which normally holds the upper arm of the detent 32 down, as shown in Fig. 3, thus keeping the engaging part of the latter out of action, rides off the said arm and permits the spring 41 to move the detent into holding relation with the car contact, as shown in Fig. 4. The door-controlled detent is thus effective while the car is at the landing to prevent unlocking of the controller while the door is open. The controller lever is therefore held locked during the remainder of the opening movement of the door, with the exception of a momentary period near the beginning when the part 10 rides over the arm 39 of the pivoted device 37. In practice, however, the operator keeps his foot on the pedal during the early part of the door opening movement; and if he should remove his foot the momentary disengagement of the detent 32 by releasing the contact will permit the latch 3 to be urged outward by its spring 42 and thus cause the lug 8 to stop the door, thus warning the operator to hold the pedal down until this point is passed. The controller lever remains locked during the closing movement of the door up to the point when part 10 reengages the arm 39. This disengages the detent 32 from the car contact and enables the operator to get a quick start from the floor while the door is completing its closing movement; but, even should the door fail to close entirely, it cannot be pushed open beyond the limited distance fixed by the first locking lug 8. Ordinarily, however, the part 10 will pass behind the second locking lug 9 which holds the door closed.

The car parts are returned to normal position by gravity, the rod 23 being sufficiently heavy for the purpose, but manifestly a spring may be provided to secure return. The car parts or mechanism are

self-restoring when freed from the restraint of the detent so that if the operator takes his foot from the pedal under these conditions, the pedal-operated shoe will automatically return to its initial position. The locking lugs 8 and 9 are beveled on their rear sides, as shown, so that in event of the bar 3 being held forward by its spring when the door is closing the part 10 is able to latch by the lugs without hindrance. The beveling of the portion 35 of the detent 32 permits the car contact 15 to latch by it, in event of the detent being in the path of this contact when the latter is projected outward; and being in the form of a roller it reduces friction in event of the car contact being pushed against it while the car is still moving.

Means are provided for reliably holding the rock member 24 in each of the rocked or extreme positions, in which it is left by the lever in the latter's outward excursion, so that on the return movement the member will be properly reengaged by the lever in order to be rocked in the reverse direction. To this end the rock member or an element 52 thereon is adapted for sliding movement in addition to the rocking movement, for the purpose of engagement with and disengagement from suitable coöperative means, such as pins 53 and 54 projecting upward from the controller casing at opposite sides of the central position of the rock member. The construction may be considerably varied, but as shown the element 52 is an elongated block mounted slidably on top of the rock member and guided and retained by means of a screw 55 projecting upward from said member within a longitudinal slot 56 in the slide, and another screw 57 projecting downward from the slide through a slot 58 in the rock member. A spring 59 in the slot 58, acting against the screw 57, urges the slide forward; while a bead 60 on the controller lever is adapted to bear against the end of the slide to shift the same rearward against the action of the spring. The parts are so arranged that when the rock member arrives at one of its extreme positions, at or about the time when the lever moves away from it during the remainder of the lever's outward excursion, the head of the screw 57 is advanced by the spring 59 and at the outer side of the pin 53, so that the latter blocks any return rocking movement of the member 24 until the lever is swung back again, picking up the member and pressing the slide 52 and screw 57 rearward. The same action takes place in respect to the abutment 54, when the rock member is rocked to its other extreme position. The extent of rocking movement of the member is limited by screws 61 and 62, which project upward, at opposite sides of the tailpiece 26, from the bracket 63 on which the rock member is ful-

erumed. These elements, therefore, co-operate with the pins 53 and 54 and the slide 52 to lock the rock member against accidental displacement in either direction 5 when in its predetermined rocked positions. Inasmuch as the upper end of the lever locking rod 23 is blocked by the tail-piece when the controller lever is not in neutral position, it is possible that injury might result to some of the parts or connections in event of pressure being applied to the pedal under such circumstances. For this reason a normally substantially rigid spring is inserted as a connection between the pedal and 10 the parts operated thereby; and in the preferred construction illustrated more particularly in Fig. 10 the pedal plunger is composed of relatively movable parts between which the spring 73 is confined under 15 compression. To this end the lower part 64 of the plunger is made hollow while from the button 68 or foot-piece proper depend a rod or long screw 65 adapted to enter the lower part and a sleeve 66 to encircle the 20 same. In assembling, the spring is placed around the screw against a washer 67 beneath the head thereof, and the screw then threaded into the button, which confines the spring at the other end. This unit construction is then slipped into telescopic relation with the part 64, where it is supported merely by the washer at the lower end of the 25 spring resting on the upper end of this part. The spring as thus confined is under a sufficient degree of compression to be substantially incompressible during the normal operation of the mechanism, thus allowing the pedal to project the car shoe. If, however, the controller locking rod 23 is blocked by 30 the solid part of the tail-piece with which it co-operates, or if other obstacle is encountered, and a considerable degree of pressure is applied to the pedal, the spring will yield, thus protecting the mechanism from injury. 35 The spring constitutes a thrust connection between the button 68 and the part 64, and may be removed with the button without releasing it from compression.

The particular construction of the circuit-controlling means 28 is not essential to the invention, but that shown is regarded as desirable. The slide bar 16 is provided at opposite sides with insulated contact plates 69 and 70, which have sliding engagement 40 with spring-pressed contacts 71 and 72. Such contacts are of known construction and do not require special illustration. The contacts 71 form terminals of the car circuit, and the contacts 72 terminals of the 45 floor light circuit. The relative arrangement is such that normally the contact plate 69 touches both of the contacts 71, so that the car circuit is closed at this point, while the plate 70 is engaged by only one of the 50 contacts 72 of the lamp circuit, which is con-

sequently open. When the slide bar is moved forward to project the car contact, this condition is reversed.

The internal construction of the car controller and the means whereby it controls the 70 operating circuits has not been illustrated, since such matters are well understood by those skilled in the art. Where in the appended claims parts are described as being at a landing, it will be understood that a location immediately at or below the landing floor is not necessarily implied, but such location that the parts are in operative relation to the car when the latter is at the 75 landing.

While the preferred embodiment of the invention has been illustrated and described in detail, it is recognized that numerous changes and modifications may be devised without departing from essentials and accordingly the invention is not to be limited to the precise features of construction shown.

What is claimed as new is:

1. In an elevator safety system, the combination with a car, a controller lever thereon, and a landing door, of means at the landing for locking the landing door, a pedal and a thereby operable train of mechanism on the car mounted separately and 90 independently of the controller lever, said train of mechanism including portions for unlocking the door-locking means and for locking the controller lever in neutral position, means controlled by the landing door 95 for holding said train of mechanism in actuated condition only when the car is at the landing, and means whereby said mechanism automatically returns to normal condition when freed by the closing of the door 100 from the restraint of said holding means.

2. In an elevator safety system, the combination with a car, a controller lever thereon, and a landing door, of means at the landing for locking the landing door, a 110 pedal and a thereby operable train of mechanism on the car mounted separately and independently of the controller lever, said train of mechanism including portions for unlocking the door-locking means and for 115 locking the controller lever in neutral position, a movable device at the landing arranged to be controlled by the door and to hold said train of mechanism in actuated condition when the car is at the landing, and 120 means whereby said mechanism automatically returns to normal condition when freed by the closing of the door from the restraint of said movable device.

3. In an elevator safety system, the combination with a car, a controller lever thereon, and a landing door, of means at the landing for locking the landing door, a 125 pedal and a thereby operable train of mechanism on the car mounted separately and in- 130

dependently of the controller lever, said train of mechanism including portions for unlocking the door-locking means and for locking the controller lever in neutral position, a movable positive holding device constructed and arranged to be controlled by the landing door and to hold said train of mechanism in actuated condition only when the car is at the landing, and means whereby said mechanism automatically returns to normal condition when freed by the closing of the door from the restraint of said holding device.

4. In an elevator safety system, the combination with a car, a controller lever thereon, and a landing door provided with a projection, of means at the landing for locking the landing door, a pedal and a thereby operable train of mechanism on the car mounted separately and independently of the controller lever, said train of mechanism including portions for unlocking the door-locking means and for locking the controller lever in neutral position, a pivoted member mounted at the landing and constructed to coöperate on the one hand with said door projection and on the other hand with the train of mechanism on the car so as to hold the latter in actuated condition while the door is open, and means whereby said mechanism automatically returns to normal condition when freed by the closing of the door from the restraint of said pivoted member.

5. In an elevator safety system, the combination with a car, a controller lever thereon, and a landing door provided with a projection, of means at the landing for locking the landing door, a pedal and a thereby operable train of mechanism on the car mounted separately and independently of the controller lever, said train of mechanism comprising branches terminating, respectively, in an external shoe for unlocking the door-locking mechanism and in a controller lever locking element, the latter normally separate from said lever, a movable holding device at the landing arranged to be controlled by the door projection and to hold the car shoe and the connected train of mechanism in actuated condition while the door is open, and means whereby said mechanism automatically returns to normal condition when freed by the closing of the door from the restraint of said holding device.

6. In an elevator safety system, the combination with a car, a controller lever thereon, and a landing door provided with a projection, of means at the landing for locking the landing door, a pedal and a thereby operable train of mechanism on the car mounted separately and independently of the controller lever, said train of mechanism having two branches, one branch comprising an external shoe for unlocking the door-locking means and the other branch com-

prising an upwardly-acting controller lever locking rod normally separate from the controller lever, a movable holding device at the landing arranged to be controlled by the door projection and to hold the car shoe and the connected train of mechanism in actuated condition while the door is open, and means whereby said mechanism automatically returns to normal condition when freed by the closing of the door from the restraint of said holding device.

7. In an elevator safety system, the combination with a car, a controller lever thereon, and a landing door, of means at the landing for locking the landing door, a pedal and a thereby operable train of mechanism on the car mounted separately and independently of the controller lever, said train of mechanism comprising two branches, one branch terminating in an external shoe for unlocking the door-locking means and the other branch, which is normally separate from the controller lever, being constrained and arranged to lock the controller lever in neutral position and to prevent operation of the mechanism when the controller lever is out of neutral position, means controlled by the landing door for holding said train of mechanism in actuated condition only when the car is at the landing, and means whereby said mechanism automatically returns to normal condition when freed by the closing of the door from the restraint of said holding means.

8. In an elevator safety system, the combination with a car, a controller lever thereon, and a landing door, of means at the landing for locking the landing door, a pedal, a train of mechanism on the car mounted separately and independently of the controller lever, a yielding connection between the pedal and said mechanism, said train of mechanism comprising branches terminating, respectively, in an external shoe for unlocking the door-locking means and in a member constructed and arranged to lock the controller lever in neutral position and to have its movement barred when the controller lever is out of neutral position, means controlled by the landing door for holding said train of mechanism in actuated condition only when the car is at the landing, and means whereby said mechanism automatically returns to normal condition when freed by the closing of the door from the restraint of said holding means.

9. In an elevator safety system, the combination with a landing door and a lock for the same, a car, and a controller located at one side of the car, of a pedal on the car, a movable car shoe for unlocking the door lock, controller-locking means, connections beneath the car floor from the pedal to the car shoe on the one hand and laterally and

thence upwardly to the controller-locking means on the other hand, and a detent at the landing controlled by the door and adapted to hold the pedal-operated instrumentalities in actuated condition while the door is unlocked.

10. In an elevator safety system, the combination with a landing door and a lock for the same, a car, and a controller, of a pedal on the car and car mechanism operable thereby, said mechanism including a shoe for unlocking the door lock and means for locking the controller, the car mechanism and pedal being separate from the controller, means for preventing the operation of said mechanism to release the door lock except when the controller is in mid-position, and a detent at the landing controlled by the door and adapted to hold the pedal-operated instrumentalities in actuated condition while the door is unlocked.

11. In an elevator safety system, the combination with a landing door and landing mechanism comprising a lock for the door and a contact movable to release the door lock, of a car, a coöperative contact on the car, a pedal connected therewith, a controller lever on the car, a member having means of engagement with the controller lever and mounted to be rocked thereby about a vertical axis, said member being provided with an opening, and an upright rod below said member, the rod being connected with the pedal and adapted to enter said opening to lock the controller when the latter is in mid-position.

12. In an elevator safety system, the combination with a landing door and landing mechanism comprising a mechanical lock for the door and a contact directly connected with the door lock and movable to release the same, of a car, a coöperative contact thereon, a pedal for mechanically operating said coöperative contact to unlock the landing door, a controller on the car, a control circuit, a switch controlling the same, and a train of connections on the car between the pedal and said switch whereby the controller is rendered inoperative by the depression of the pedal to unlock the door, said train being free to return to normal position upon removal of the foot from the pedal.

13. In an elevator safety system, the combination with a landing door and a lock therefor, of a controller in the car, car mechanism comprising a pedal on the car separate from the controller, a contact carried by the car for unlocking the door lock, a controller lock normally separate from the controller, and mechanical connections on the car from the pedal to said contact and controller lock, and a detent adapted to engage and hold the car contact in actuated

position and to be disengaged by the door in closing, said car mechanism being self-restoring when freed from the restraint of said detent.

14. In an elevator safety system, the combination of a landing door having a downward projection operative in the gap between the car and landing, a door-locking member mounted on the face of the elevator shaft below the landing floor adapted to bar movement of said projection, a car controller, a pedal on the car separate from the controller, a contact carried by the car adapted to unlock the door-lock, a device normally separate from the controller for locking the same, mechanical connections wholly on the car extending from said pedal to the car contact and to the controller-locking device, and an automatic spring-urged detent for holding the car contact in actuated position, said detent being adapted to be restored to normal position through the action of the door in closing and the car contact and therewith connected parts being adapted thereupon to return automatically to their normal positions.

15. An elevator safety system, comprising the combination of a landing door lock, a car shoe movable to unlock the same, a controller lock normally separate from the controller, an operator's device on the car separate from the controller, connections between the car shoe and controller lock, said connections being operated by the operator's device to unlock the landing door and at the same time lock the controller and adapted to return automatically to initial position when permitted, the controller being normally operable without operating the car shoe, and a spring-pressed detent at the landing constructed to engage directly with the car shoe and thereby hold the same and the therewith-connected controller lock in the actuated condition while the door is open, the detent being shifted against the action of the spring by the door in closing to permit the restoration of the car shoe and its connections on the car.

16. An elevator safety system, comprising the combination of a lock at the landing for locking the landing door, said lock having a contact portion whereby it may be unlocked, a car shoe adapted to coact with said contact portion and movable to unlock the door lock, a controller lock normally separate from the controller, an operator's device on the car separate from the controller, connections wholly on the car between said shoe and controller lock and whereby both are operated by said operator's device, the controller being normally operable without operating the car shoe or said connections, means for preventing the projection of said shoe except when the controller is in mid-

position, and a device mounted at the landing in conjunction with the door lock and controlled by the door whereby the car shoe and controller lock are held in the actuated condition while the door is open.

17. An elevator safety system, comprising the combination of a projecting iron on a landing door, a lock at the landing for locking said door by barring movement of its projecting iron, said lock having a contact portion whereby it may be unlocked, a car shoe adapted to coat with said contact portion to unlock the door lock, a controller lock normally separate from the controller, an operator's device on the car separate from the controller, connections wholly on the car between said shoe and controller lock and whereby both are operated by said operator's device, means for preventing the projection of said shoe except when the controller is in mid-position, the controller being normally operable without operating the car shoe or said connections, means for holding the car shoe and therewith-connected controller lock in the actuated condition to prevent starting of the car while the door is open, said means comprising a member mounted at the landing in conjunction with the door lock to be engaged and operated by said door-iron, and means whereby the shoe and the therewith connected parts on the car return to normal condition when permitted.

18. An elevator safety system, comprising the combination of a projecting iron on a landing door, a lock at the landing for locking said door by barring movement of its projecting iron, said lock having a contact portion whereby it may be unlocked, a car shoe adapted to coat with said contact portion to unlock the door lock, a controller lock normally separate from the controller, an operator's device on the car separate from the controller, connections wholly on the car between said shoe and controller lock and whereby both are operated by said operator's device, means for preventing the projection of said shoe except when the controller is in mid-position, the controller being normally operable without operating the car shoe or said connections, means for holding the car shoe and therewith-connected controller lock in the actuated condition to prevent starting of the car while the door is open, said means comprising a lock member at the landing mounted to turn about a horizontal axis perpendicular to the face of the shaft and having a portion to engage with the door-iron and another portion to effect the holding of the car shoe, and means whereby the shoe and the therewith connected parts on the car return to normal condition when permitted.

19. In an elevator safety system, the combination of a landing door having a down-

ward projection operative in the gap between the car and landing, a spring-urged door-locking member pivoted on a vertical axis on the face of the elevator shaft below the landing floor and having a horizontally extending arm formed with a plurality of locking lugs and located between the door projection and the face of the shaft, and a contact on the car adapted to be projected to press said locking member backward relatively to the face of the shaft to release the door projection.

20. In an elevator safety system, the combination with a landing door having a downward projection operative in the gap between the car and landing, a flat case applied vertically to the face of the elevator shaft below the landing floor, a spring-urged swinging locking member in said case between the door projection and the face of the shaft, said locking member having a horizontally extending portion provided with a plurality of locking lugs, and a spring-urged detent in the case adapted to be acted upon by said door projection, of a controller on the car, a lock for the controller, a car contact adapted to be projected to press said locking member backward out of locking position and to be engaged and held by said detent, and a pedal on the car connected to operate both said controller and said contact.

21. In an elevator safety system, the combination of a landing door having a downward projection operative in the gap between the car and landing, a door-locking member pivoted on a vertical axis on the face of the shaft below the landing floor and having upper and lower arms extending laterally in the same direction from the pivotal axis, one of said arms being formed with a locking shoulder to hold said projection and the other arm having a contact portion, a spring urging said locking member in a direction away from the wall of the shaft, and a self-restoring pedal-operated shoe on the car adapted to be projected against said contact portion to press the locking arm out of engagement with said projection.

22. In an elevator safety system, a landing door having a part projecting downward therefrom, a horizontally extending latch mounted on the face of the shaft to swing on a vertical axis and having locking lugs spaced lengthwise thereon to retain the part on the door, and detent mechanism adjacent said lock constructed and arranged to be shifted to releasing position by said door projection when the latter reaches the first of its locking positions in the door closing movement, in combination with a car having a controller, and mechanism on the car for unlocking the door locking member and

- multaneously rendering said controller inoperative, said detent mechanism engaging a portion of the car mechanism to hold the same in shifted position while the door is 5 open.
23. In an elevator safety system, a landing door, locking mechanism operative to hold the door against opening movement when closed and also when at a predetermined distance from closing, a contact connected with said locking mechanism, mechanism on the car for rendering the car controller inoperative having connected therewith a contact to coöperate with the landing contact, and operator's means for shifting said mechanisms so as to unlock the door and render the controller inoperative, in combination with a detent whereby the car mechanism is held in shifted position, and means whereby said car mechanism is freed to restore control of the car to the operator when the landing door in closing reaches the first of its locking positions.
24. In an elevator safety system, a landing door, locking mechanism operative to hold the door against opening movement when closed and also when at a predetermined distance from closing, and a contact connected with said locking mechanism, in combination with a car controller, means on the car to lock the controller, a pedal on the car to operate said controller locking means, a car contact also connected with the pedal to operate the landing contact, a detent operative to hold said car contact in shifted position, and means for disengaging said detent when the first locking position is reached in the closing of the door.
25. In an elevator safety system, a landing door, locking mechanism operative to hold the door against opening movement when closed and also when at a predetermined distance from closing, and a contact connected with said locking mechanism, in combination with a car controller, means on the car to lock the controller, a pedal on the car to operate said controller locking means, a car contact also connected with the pedal to operate the landing contact, a detent operative to hold said car contact in shifted position, and means whereby the door retracts said detent approximately when the first locking position is reached and again when approximately closed.
26. In an elevator safety system, a landing door, locking mechanism operative to hold the door against opening movement when closed and also when at a predetermined distance from closing, a contact connected with said locking mechanism, a cooperative contact on the car, controller locking mechanism also on the car, and an operator's device on the car for operating both the car contact and the controller locking mechanism, in combination with a de-
- tent at the landing for engagement with the car contact, and means whereby the door retracts said detent approximately when the first locking position is reached and again when approximately closed.
27. In an elevator safety system, the combination with a landing door, means for locking the same in two positions, a car having a controller, and mechanism on the car whereby the operator may unlock the landing door and simultaneously effect locking of the controller, in combination with a detent for holding the car mechanism in shifted condition, and members spaced correspondingly to the locking positions of the door and adapted to be engaged successively by a part on the door to retract the detent.
28. In an elevator safety system, the combination with a landing door, means for locking the same in two positions, a car having a controller, and mechanism on the car whereby the operator may unlock the landing door and simultaneously effect locking of the controller, in combination with two spaced pivoted elements arranged to be engaged successively by a part on the door and having a connection between them whereby one moves the other, one of said elements having means to engage and hold a part of the car mechanism in shifted position.
29. In an elevator safety system, the combination with a landing door, means for locking the same in two positions, a car having a controller, and mechanism on the car whereby the operator may unlock the landing door and simultaneously effect locking of the controller, in combination with two spaced bell-crank elements connected by a link and adapted to be engaged successively by a part on the door, one of said elements having a portion to engage and hold a part of the car mechanism in shifted position.
30. In an elevator safety system, the combination with a landing door, means for locking the same in two positions, a car having a controller, and mechanism on the car whereby the operator may unlock the landing door and simultaneously effect locking of the controller, in combination with a detent mechanism comprising a portion adapted to engage a part of the car mechanism to hold the same shifted, said portion having a beveled face to permit said part to latch by the same, and members connected with each other and adapted to be engaged successively by a part on the door to disengage the detent portion.
31. In an elevator safety system, the combination with a landing door, means for locking the same in two positions, a car having a controller, and mechanism on the car whereby the operator may unlock the landing door and simultaneously effect locking of the controller, in combination with

- detent mechanism comprising an element having a beveled member mounted rotatably thereon to engage behind a part of the car mechanism and to permit the same to latch by it, and a second element spaced from and connected with the first, said elements being adapted to be engaged successively by a part on the door to disengage said beveled member from the part on the car.
32. In an elevator safety system, a landing door having a part projecting downward therefrom, a horizontally extending latch mounted on the face of the shaft to swing on a vertical axis and having locking lugs spaced lengthwise thereon to retain the part on the door, and horizontally spaced pivoted devices arranged to be engaged successively by said part, in combination with a car having a controller, and mechanism on the car for retracting the latch and simultaneously rendering said controller inoperative, one of said pivoted devices being a 50 detent adapted to engage and hold a part of said car mechanism in shifted position.
33. In an elevator safety system, a landing door having a projection, a locking device having horizontally spaced lugs coöperative with said projection, a car having a controller, mechanism on the car for retracting said locking device and simultaneously rendering the controller inoperative, and detent means adapted to engage and hold a part of said car mechanism in shifted position and having portions arranged to be actuated successively by the door in closing to disengage the detent.
34. In an elevator safety system, a landing door having a part projecting therefrom, a locking device having longitudinally spaced locking portions coöperative with said projection, mechanism on the car capable of actuation by the operator to retract said locking device and simultaneously render the controller inoperative, and detent means on the landing adapted to engage and hold a part of said car mechanism in shifted position and having portions arranged to be actuated successively by said projecting door part in closing to disengage the detent.
35. In an elevator safety system, the combination with mechanism at a landing including a contact, of a car having a controller lever, a contact on the car coöperative with the landing contact, a rock member having a forked portion adapted to be engaged by said lever to rock the member in one direction or the other according to the direction of movement of the lever, means connected with the car contact and adapted to engage said rock member to lock the same and the controller lever central, and means for holding said member against displacement in either direction when in its extreme positions.
36. In an elevator safety system, the combination with a controller lever, of a rock member having a forked portion projecting into the path of the lever whereby the member is adapted to be rocked reversely by the respective back and forth movements of the lever, and means whereby said member is locked in each of its rocked positions and unlocked by the action of the lever.
37. In an elevator safety system, the combination with a controller lever, of a rock member adapted to be engaged and moved by the controller lever in one direction or the other according to the direction of movement of the lever, an element movable on said member under the control of the controller lever, and means coöperative with said element to hold the rock member against displacement in either direction in each of its rocked positions.
38. In an elevator safety system, the combination with a controller lever, of a rock member adapted to be engaged and moved by the controller lever in one direction or the other according to the direction of movement of the lever, an element mounted 85 slidably on said rock member, stationary abutments adapted to coöperate with said element to retain the rock member in each of its extreme positions, a spring for urging said element to engage said abutments, the 90 slide being arranged to be disengaged therefrom by the action of the controller.
39. In an elevator safety system, the combination with a controller lever, of a rock member adapted to be engaged and moved 100 by the controller lever in one direction or the other according to the direction of movement of the lever, means coöperative with said rock member to lock the controller lever in mid-position, and means for locking said member against displacement when in its extreme positions disengaged from the lever, the said means comprising a 105 spring-pressed element on said rock member, and coöperative means mounted on a 110 suitable stationary part, said element engaging automatically with said coöperative means when the lever leaves the rock member and being disengaged by the lever when the latter in its return movement picks up 115 the rock member.
40. In an elevator safety system, the combination with a landing door, a lock therefor, and a contact at the landing for releasing said lock, of a car having a controller lever, means for locking said controller lever in neutral position, a contact on the car movable to actuate the landing contact, an operator's device on the car, and connections whereby said device operates 120 both the car contact and the lever locking means, said lever locking means being adapted to block actuation of said connections when the controller lever is out of neutral position, and said connections including a 125 130

normally substantially rigid spring adapted to yield in event of operation of the operator's device when the connections are blocked.

- 5 41. In an elevator safety system, the combination with a landing door, a lock therefore, an elevator car having a controller lever, and a lock for said lever, of a pedal on the car for releasing the door lock and
- 10 applying the lever lock, said pedal having a plunger composed of parts movable relatively to each other, and a normally substantially rigid spring confined as a connection between said parts.
- 15 42. In an elevator safety system, comprising suitable mechanism on a car, a pedal for operating said mechanism having, in combination with a lower part, a removable upper part comprising a foot-piece, a spring, and a member secured to the foot-piece and coöperating therewith to confine the spring to the foot-piece, said spring being arranged to be compressed between the foot-piece and the lower part by
- 20 pressure applied to the former.
- 25 43. In an elevator safety system, the combination with a door at a landing and a con-

troller in the car, of means for locking the door when within a predetermined distance of closing, means for locking the controller, 30 foot-operated mechanism on the car for unlocking the door lock and locking the controller lock, and means whereby the door in closing unlocks the controller approximately at such predetermined distance. 35

44. In an elevator safety system, the combination of a door at a landing, means for locking the door in closed position and at a predetermined distance from closing, a controller in the car, means for locking the controller, and mechanism partly on the car and partly at the landing and including an operating pedal on the car whereby the controller is locked when the door is unlocked 45 and vice-versa.

In testimony whereof, I have signed my name to this specification in the presence of two subscribing witnesses.

WILLIAM T. DUNFORD.
